US00D491670S

(12) **United States Design Patent** (10) Patent No.: **US D491,670 S**
 Leung et al. (45) Date of Patent: ** Jun. 15, 2004

(54) **SAUNA**

(76) Inventors: **Anthony Kit Lun Leung**, 2B 41
 Braemar Hill Road, North Point, Hong
 Kong (CN); **Brenda P. K. Yue**, Block
 7, Flat E, Sceneway Garden Lam Tin,
 Kowloon, Hong Kong (CN); **Kam Fai
 Fung**, Block 7, Flat D, 2F Melody
 Garden Tuen Mun, Hong Kong (CN)

(**) Term: **14 Years**

(21) Appl. No.: **29/163,233**

(22) Filed: **Jun. 28, 2002**

(51) LOC (7) Cl. **23-02**

(52) U.S. Cl. **D24/203**

(58) Field of Search **D24/203; 392/403,
 392/406, 405; 4/535, 537**
